MOLTEN METAL PUMP

Filed April 29, 1936

UNITED STATES PATENT OFFICE

2,110,379

MOLTEN METAL PUMP

Frank Lannert, Chicago, Ill., assignor to Paragon Die Casting Company, Chicago, Ill., a corporation of Illinois

Application April 29, 1936, Serial No. 76,899

9 Claims. (Cl. 22—70)

This invention relates to pumps such as are used in die-casting machines to force molten metal into the die. It is, of course, desirable that there be no leakage or "wash" between the plunger and cylinder, as such leakage makes it difficult or impossible to force the molten metal into the die under the desired degree of pressure with certainty and uniformity. Moreover, such wash causes erosion of the plunger and cylinder, which becomes progressively worse as the clearance between the plunger and the cylinder increases.

Heretofore the plunger has been of solid construction and of such diameter in the beginning as to have a snug working fit in the cylinder. It has, however, been impossible to prevent seepage of the molten metal past the plunger, with consequent erosion, so that the useful life of the plunger has been relatively short and it has been necessary to bore out the cylinder at relatively frequent intervals. Furthermore, inasmuch as the plunger is immersed in the molten metal, it has been necessary for the workman to disconnect and withdraw the plunger upon shutting down the machine at noon and night, and to replace the plunger upon resuming operation of the machine, for the reason that if the plunger were left at rest in the molten metal, there would be danger that the plunger would stick to the cylinder, particularly if the heat became excessive through failure or misoperation of the thermostatic control usually provided.

The object of the present invention is to overcome the objections and disadvantages arising in connection with the use of the types of plungers heretofore employed. This object I have attained by providing a plunger comprising a body having ample clearance between it and the cylinder wall, which body carries a plurality of ring segments which are arranged to be forced into proper working contact with the cylinder wall by the pressure on the molten metal in the injection stroke, the segments being so arranged with relation to one another as to prevent seepage or wash of the molten metal past the plunger.

In the accompanying drawing, which illustrates several of the various possible embodiments of my invention,

Figure 1 is a sectional view of a molten metal pump provided with a plunger embodying the features of the invention.

Fig. 2 is an axial sectional view of the plunger shown in Fig. 1 upon an enlarged scale.

Fig. 3 is a view similar to that of Fig. 2, but showing the plunger in engagement with the

cylinder wall, as occurs during the injection stroke.

Figs. 4, 5 and 6 are transverse sectional views taken in the planes of lines 4—4, 5—5 and 6—6, respectively, of Fig. 2.

Fig. 7 is a view similar to that of Fig. 2 but showing an alternative construction.

Fig. 8 is a section on line 8—8 of Fig. 7.

Fig. 9 is a view similar to that of Fig. 2, but showing an alternative construction, which at present is the preferred form.

The plunger construction herein disclosed is not limited to use with a pump of the character shown in Fig. 1, but, on the contrary, it may be used in molten metal pumps of various constructions. Fig. 1 will, however, serve to impart an understanding of the practical conditions under which the improved plunger is used. In this view, 1 is a melting pot containing molten metal *a*. In the pot 1 is a pump cylinder 2. A port 3 in the cylinder permits molten metal to flow from the melting pot 1 into the pump cylinder. The lower end of the pump cylinder communicates with a discharge passage 4 that leads to the die (not shown).

The plunger comprises a body 5, herein shown as cylindrical. The body may be connected in any desired way to a means for reciprocating the plunger. Ample clearance is provided between the body 5 and the cylinder wall, as shown in Fig. 3, so as to obviate any danger that the body shall stick to the cylinder. In the lower end of the body 5 is an axial screw-threaded opening 6 into which is screwed a stud 7. The stud 7 has an annular shoulder 8 that stops against a similar shoulder on the body 5. On the lower end of the stud 7 is a head or flange 9.

On the stud 7 is a ring 10 adapted to rest upon the head 9, said ring being herein shown as of the same external diameter as the body 5. Between the ring 10 and the lower end of the body 5 is a set of concentric ring segments arranged to form two inner rings and two outer rings. The lower inner ring consists of segments 11, 12 and 13 (Fig. 6). The upper inner ring consists of segments 14, 15 and 16 (Fig. 5). Surrounding these rings is a lower outer ring formed of the segments 17, 18 and 19 (Figs. 5 and 6), and an upper outer ring composed of the segments 20, 21 and 22 (Fig. 4). The ring segments are preferably hardened and ground. The outer rings are in contact with each other; and the inner rings are in contact with each other.

The upper side of the ring 10 is beveled and the lower edges of the ring segments 11, 12, 13, 55

17, 18 and 19 are correspondingly beveled for contact with the ring 10. Similarly, the lower end of the body 5 is beveled and the upper ends of the segments 14, 15, 16, 20, 21 and 22 are beveled to make contact with the body 5. It will be seen that pressure of the ring 10 against the molten metal in the cylinder 2 will spread the ring segments radially outward so as to force the segments 17, 18, 19, 20, 21, and 22 into contact with the cylinder wall and also force the segments 11, 12, 13, 14, 15 and 16 outwardly into contact with the segments 17, 18, 19, 20, 21 and 22.

As shown in Figs. 2, 4, 5 and 6, there is sufficient clearance between the stud 7 and the inner rings 15 so as to produce an annular space 23, whereby the rings may be placed under internal pressure of molten metal, as will now be explained.

The expansion of the ring segments into contact with the cylinder wall under the pressure of 20 the ring 10 provides a space 23^a (Fig. 3) between the head 9 and the ring 10, into which molten metal may flow. The diameter of the central opening 23^b (Fig. 3) of the ring 10 is sufficiently greater than the diameter of the stud 7 so that 25 the molten metal entering the space 23^a between the head 9 and the ring 10 may flow up into the space 23^b and thence into the space 23 between the stud 7 and the inner ring segments 11, 12, 13, 14, 15 and 16 to force or assist in forcing the 30 ring segments outwardly against the cylinder.

When the rings are expanded into contact with the cylinder, there is a slight clearance or space between adjacent ends of the ring segments, but it will be noted that these spaces are staggered 35 so as to limit the extent to which molten metal may flow up. Thus, considering, Figs. 3 and 6, molten metal between the periphery of the ring 10 and the cylinder wall can flow up into the spaces between the ends of the segments 17, 18 40 and 19, but cannot flow any higher because the segments 20, 21 and 22 (Figs. 3 and 4) are offset or staggered with relation to the segments 17, 18 and 19, so that the segment 20 closes the upper end of the space between the adjacent ends 45 of the segments 19 and 17, the segment 21 closes the upper end of the space between the adjacent ends of the segments 17 and 18, and the segment 22 closes the upper end of the space between the adjacent ends of the segments 18 and 19.

50 Molten metal entering the annular space 23 (Fig. 6) between the stud 7 and the inner rings may enter the spaces between the adjacent ends of the segments 11, 12 and 13, but cannot flow any farther radially outwardly because such 55 spaces are closed by the segments 17, 18 and 19. The upper ends of the spaces between adjacent ends of the segments 11, 12 and 13 are closed by the segments 14, 15 and 16. Similarly, molten metal entering the spaces between the 60 adjacent ends of the segments 14, 15 and 16 can flow no farther, because said spaces are closed by the segments 20, 21 and 22 and by the beveled surface of the body 5.

In order to maintain the ring segments in staggered relation to one another, they are connected by dowel pins 25. One of these pins (see Fig. 6) holds the segments 13 and 18 in staggered relation, another pin (Fig. 5) holds the segments 18 and 16 in staggered relation, and the other pin (Fig. 4) holds the segments 22 and 16 in staggered relation, all of the segments being thereby maintained in proper location with reference to one another. Each pin may be fixed in one segment and loose in the other segment.

75 It will be noted that the outer ring formed of

the segments 17, 18 and 19 is higher than the inner ring formed of the segments 11, 12 and 13, thereby producing a broken joint between the two outer rings and the two inner rings.

The described arrangement of ring segments 5 produces during the injection stroke a sufficiently tight contact between the plunger and the cylinder so as to prevent the escape of molten metal past the plunger, thereby preventing erosive wash and loss of pressure.

10 While the spaces 23^a and 23^b provide a passage for the molten metal to reach the space 23, I prefer to use another arrangement which provides a freer or more direct passage. This is shown in Figs. 7 and 8. An axial duct 26 is 15 formed in the stud 7^a, said duct opening upon the lower end of the stud. The upper end of the duct communicates with a transverse duct 27, which extends to the periphery of the stud 20 so as to allow the molten metal to exert pressure upon the inner sides of the ring segments 11, 12, 13, 14, 15 and 16.

In the forms of plunger shown in Figs. 1 to 8, the area of the ring 10 which is initially exposed to the pressure of the molten metal is that 25 beyond the periphery of the head 9. In Fig. 9 I have shown a construction wherein the entire surface of the lower end of the plunger is exposed to the pressure of the molten metal for the purpose of producing radial expansion of 30 the ring segments into contact with the cylinder wall. As shown in Fig. 9, the body 5^a has an axial opening 28 in which is slidably mounted a stud 29. The upper end of the stud 29 has an annular groove 30 to receive a split ring 31. The 35 upper end of the body 5^a has a bore 28^a of sufficiently large diameter to receive the ring 31, the upper end of said bore being screw-threaded for attachment to the rod by means of which the plunger is reciprocated.

40 On the lower end of the stud 29 is a circular head 32 which is of the same diameter as the body 5^a. The upper side of the head 32 and the lower end of the body 5^a are bevelled, as in the case of the body 5 and ring 10, and between the head 32 and the body 5^a is located a set of ring segments identical with the ring segments previously described.

In assembling the plunger shown in Fig. 9, the stud 29 is inserted into the bore 28—28^a until 50 its upper end projects above the body 5^a. The split ring 31 is then placed in the groove 30 and the stud 29 drawn downwardly to place the ring 31 within the bore 28^a. The ring segments are then assembled in the space between the body 5^a and the head 32.

All of the forms of plungers herein illustrated are adapted to provide proper contact between the plunger and the cylinder so as to prevent the escape of metal past the plunger in the injection 60 stroke. As shown in Figs. 1 and 3, there is ample clearance between the body 5 and the ring 10 (or the body 5^a and the head 32) and the cylinder wall. Although the ring segments are at all times immersed in the molten metal, experience has shown that the plunger need not be withdrawn from the cylinder when the machine 65 is shut down, as the body of the plunger and the ring 10 or the head 32 do not stick to the cylinder.

70 By means of my invention, the efficiency of the plunger in operation is increased, the useful life of the plunger and the cylinder is substantially prolonged, and the necessity of disconnecting and withdrawing the plunger upon shutting down 75

the machine and replacing and connecting the plunger when the machine is again operated is obviated.

While I have illustrated and described various details, it will be understood that the invention is not limited thereto, the scope of the invention being indicated in the appended claims.

In certain of the claims which relate more particularly to the segmental rings, I have referred 10 to the body 5, stud 7 and ring 10 as a structure having an annular space in which an expansive ring or rings are located. As applied to the form shown in Fig. 9, the structure that supports the expansive ring or rings consists of the body 5^a 15 and the stud 29.

I claim as my invention:

1. In a molten metal pump of the cylinder and plunger type, said plunger comprising a body of sufficiently smaller diameter than the cylinder so 20 as to be out of contact therewith, a stud axially alined with the body and connected thereto for limited longitudinal movement and projecting from one end of the body, the projecting end of said stud having a head of sufficiently smaller 25 diameter than the cylinder so as to be out of contact therewith, the side of said head which faces the body and the end of said body which faces said head being beveled, and a series of correspondingly beveled ring segments extending 30 around said stud between said beveled surfaces and arranged to be forced by the wedging action of said beveled surfaces into contact with the cylinder on the pumping stroke of the pump.

2. In a molten metal pump of the cylinder and 35 plunger type, said plunger comprising a body, a stud axially alined with the body and connected thereto for limited longitudinal movement and projecting from one end of the body, the projecting end of said stud having a head, the side of 40 said head which faces the body and the end of said body which faces said head being beveled, and correspondingly beveled ring segments located between said beveled surfaces and arranged on the pumping stroke to be forced outwardly by the wedging action of said beveled surfaces into contact with the cylinder.

3. In a molten metal pump of the cylinder and 50 plunger type, said plunger comprising a body, a stud axially alined with the body and connected thereto for limited longitudinal movement and projecting from one end of the body, the projecting end of said stud having a head which is exposed to the pressure of the molten metal, and ring segments located between said head and the 55 end of the body and encircling the stud, and arranged to be forced outwardly into contact with the cylinder, said head having a passage leading to the surface of that portion of the stud which is encircled by the ring segments, whereby molten 60 metal may flow into contact with the concave side of the ring segments.

4. In a molten metal pump of the cylinder and 65 plunger type, said plunger comprising a body, a stud connected thereto for limited longitudinal movement and projecting from one end of the body, the projecting end of said stud having a head, and ring segments encircling the stud and located between said head and the end of the body and arranged to be forced outwardly into 70 contact with the cylinder, said stud having a passage opening upon said head and extending to the space between said head and the body to expose said segments to pressure of the molten metal internally of the segments.

5. In a molten-metal pump of the cylinder

and plunger type, said plunger comprising a body, a stud secured to and projecting axially from one end of the body, the outer end of said stud having a head of less diameter than the body, a ring slidably mounted on the stud alongside the head and of larger diameter than the head, the side of said ring which faces the body and the end of said body which faces the ring being beveled, and correspondingly beveled ring segments located between said beveled surfaces and arranged to be forced outwardly by the wedging action of said surfaces into contact with the cylinder.

6. In a molten-metal pump of the cylinder and plunger type, said plunger comprising a body, a stud rigidly secured to and projecting axially from one end of the body, the outer end of said stud having a head, a ring slidably mounted on the stud alongside the head and of larger diameter than the head, the side of said ring which faces the body and the end of said body which faces the ring being beveled, and correspondingly beveled ring segments located between said beveled surfaces and arranged to be forced outwardly into contact with the cylinder, the other side of said ring being exposed to the pressure of the molten metal to force said ring away from the head to provide space for the entrance of molten metal, there being clearance between the ring segments and the stud, which clearance is in communication with said space to permit the molten metal to exert pressure against the concave sides of the ring segments.

7. A molten-metal pump of the cylinder and plunger type, said plunger comprising a structure 35 having an annular space between its ends, and a plurality of rings in said space, there being a plurality of outer rings adapted to engage the cylinder wall and a plurality of rings within the outer rings, each of said rings comprising a plurality of segments, the joints of one outer ring being staggered with relation to the joints of the other outer ring, the joints of one inner ring being staggered with relation to the joints of the other inner ring, the joint between the outer rings 40 being staggered with relation to the joint between the inner rings, said structure having a passage opening upon the pressure end thereof and extending to said annular space to place said rings under pressure of the molten metal.

8. In a molten-metal pump of the cylinder and plunger type, said plunger comprising a structure having an annular space between its ends, and a plurality of rings in said space, there being a plurality of outer rings in contact with each other and adapted to engage the cylinder wall and a plurality of rings in contact with each other and located within the outer rings, each of said rings comprising a plurality of segments, the joints of one outer ring being staggered with relation to the joints of the adjacent outer ring, the joints of one inner ring being staggered with relation to the joints of the adjacent inner ring, the line of contact between the outer rings being staggered with relation to the line of contact 65 between the inner rings, said structure having means to place said rings under internal pressure of the molten metal.

9. In a molten-metal pump of the cylinder and plunger type, said plunger comprising a 70 structure having an annular space between its ends, and a plurality of rings in said space, there being a plurality of outer rings adapted to engage the cylinder wall and a plurality of rings within the outer rings, each of said rings com- 75

prising a plurality of segments, the joints of one outer ring being staggered with relation to the joints of the other outer ring, the joints of one inner ring being staggered with relation to the joints of the other inner ring, the joint between the outer rings being staggered relative to the joint between the inner rings, and dowel pins

connecting one segment of each inner ring to the adjacent segment of the corresponding outer ring, and a dowel pin connecting adjacent segments of their overlapping inner and outer rings to maintain all of said joints in such staggered 5 relation.

FRANK LANNERT.
